UNITED STATES PATENT OFFICE.

LEWIS F. SMALL, OF BRAINTREE, MASSACHUSETTS, ASSIGNOR TO C. C. BLAKE, INCORPORATED, OF BOSTON, MASSACHUSETTS, A CORPORATION OF NEW YORK.

LAST.

Application filed March 29, 1918. Serial No. 225,551.

To all whom it may concern:

Be it known that I, LEWIS F. SMALL, a citizen of the United States, residing at Braintree, in the county of Norfolk and State of Massachusetts, have invented certain Improvements in Lasts, of which the following description, in connection with the accompanying drawings, is a specification, like reference characters on the drawings indicating like parts in the several figures.

The present invention relates to lasts which are used in the manufacture of shoes to impart shape to the uppers thereof during the lasting operation.

The muscles of the human foot are intended to exert a tractive effort in propelling a person forward. Unfortunately, notwithstanding the boasted highly developed art of shoe making, little or no care has been taken by shoe designers to obtain a shoe construction which would permit the muscles to exert their most efficient tractive effort. This is due principally to the fact that new shoe styles are created upon questions of appearance and so designers skilled in an artistic sense have been developed instead of men of scientific tendencies who would try to analyze the needs of the foot and then design a shoe to cooperate therewith.

Consequently in order for people to walk with shoes at present constructed the feet and legs must adapt themselves to the wrong shoe construction. Any movement of the foot or leg other than is required to propel a person forward reduces the effective tractive effort exerted by the muscles, wastes energy, and produces harmful conditions in the feet. This automatic adaptation of the foot or leg in walking is particularly noticeable in the lateral twisting or rocking of the foot about the ankle bone during the time the shoe is engaged with the ground. One cause of this is due to the faulty construction of the bottom of the lasts upon which the shoes are made. These lasts have all been made heretofore so that if the bottoms thereof are engaged with a flat surface and moved thereon in the same way a shoe moves on the ground in the act of walking, the last will be seen to rock laterally. Obviously a shoe made on such a last will rock in the same manner.

The object of the present invention is to produce a last for a shoe which will allow the muscles of the foot inside the shoe to exert a forward tractive effort only, thus obviating the dangerous lateral twist of the foot in walking.

To the accomplishment of this object, and such others as may hereinafter appear, the features of the invention relate to certain constructions and arrangements of parts hereinafter described and then set forth broadly and in detail in the appended claims which possess advantages readily apparent to those skilled in the art.

The various features of the present invention will be readily understood from an inspection of the accompanying drawings, in which,

Figure 1 is a plan of a last;

Fig. 2 is a bottom plan, and

Fig. 3 is a rear end elevation.

The last embodying the features of the present invention is provided with an upper shaping surface 1 and a bottom 2. The surface 1 has a cone 3, containing the usual spindle bushing 4 therein, and an instep ridge 5. The bottom of the last comprises a heel seat 6, a shank 7, and a forepart 8. In order to obtain a balanced construction I construct the bottom of my last so that the median line 9 bisects the end curvatures of the toe and heel and divides the heel seat 6 into equal portions (Fig. 2).

The upper shaping surface 1, when cut by a plane passing through the median line 9 bisects the end curvatures at the ends of the last. The median line 10 on the upper shaping surface 1 intersects the center line of the cone 3 and coincides with the ridge 5 (Fig. 1).

The bottom of the last is constructed so that any series of lines drawn at right angles to the median line 9 throughout the length of the last are arranged in parallel planes (Fig. 3). With this construction the shoe made on the last will move on the ground during the act of walking in a forward manner without any lateral rocking motion. Obviously with this shoe the entire tractive effort of the foot muscles is exerted in propelling the wearer forward.

What is claimed as new, is:

1. A last having an upper shaping sur-

face and a bottom thereon, any series of lines across the bottom of the last at right angles to the median line throughout the length of the last lying in parallel planes.

5 2. A last having an upper shaping surface and a bottom thereon, said bottom comprising a heel seat and a forepart, the effec-

tive tread surface of the heel seat lying in a plane parallel to the planes of any series of lines across the forepart of the last at 10 right angles to the median line thereof.

In testimony whereof I have signed my name to this specification.

LEWIS F. SMALL.
